(57) **CLAIM**

I claim the ornamental design for a portable headboard panel, as shown and described.

DESCRIPTION

FIG. 1 is a perspective view of a portable headboard panel, showing my new design;

FIG. 2 is a front elevational view thereof;

FIG. 3 is a top plan view thereof;

FIG. 4 is a bottom plan view thereof;

FIG. 5 is a left-side elevational view thereof;

FIG. 6 is a right-side elevational view thereof; and,

FIG. 7 is a rear elevational view thereof.

The broken lines showing additional headboard panels in FIG. 1 and features on the rear surface of the design in FIG. 7 depict environmental matter and form no part of the claimed design.
